US00D915299S

(12) **United States Design Patent** (10) **Patent No.:** **US D915,299 S**
(45) **Date of Patent:** **** Apr. 6, 2021**

(54) **WIRING TERMINAL**

(71) Applicants: **DINKLE ENTERPRISE CO., LTD.**,
New Taipei (TW); **DINKLE ELECTRIC MACHINERY (CHINA) CO., LTD.**, Jiangsu (CN)

(72) Inventor: **Shang-Tsai Wu**, New Taipei (TW)

(73) Assignees: **DINKLE ENTERPRISE CO., LTD.**,
New Taipei (TW); **DINKLE ELECTRIC MACHINERY (CHINA) CO.. LTD.**, Jiangsu (CN)

(**) Term: **15 Years**

(21) Appl. No.: **29/670,291**

(22) Filed: **Nov. 15, 2018**

(51) LOC (13) Cl. **13-03**

(52) U.S. Cl.

USPC **D13/154**

(58) **Field of Classification Search**

USPC D13/110, 120, 123, 133, 154, 118, 146,
D13/147, 149, 153, 178, 184, 199

CPC H01R 4/183; H01R 4/184; H01R 4/185;
H01R 13/6471; H01R 13/6585

See application file for complete search history.
